His Attorney.

UNITED STATES PATENT OFFICE.

BENJAMIN K. FISHER, OF ST. LOUIS, MISSOURI.

CIGARETTE-ROLLING DEVICE.

Application filed July 21, 1927. Serial No. 207,362.

This invention relates to improvements in a cigarette rolling device, and consists in the novel construction hereinafter described.

An object of the invention is to provide a device which is adapted, by manual manipulation, to roll cigarettes.

Another object of the invention is to provide a device of the kind mentioned that may be associated with a tobacco pouch, and by which cigarettes may be rolled with facility without spilling the tobacco out of which the cigarettes are made.

Additional advantages of the invention will be apparent from the following detailed description thereof, taken in connection with the accompanying drawing, in which

Fig. 1 is a plan view of a pouch with the cigarette rolling device incorporated therein.

Fig. 2 is a detail view showing the position of the parts adjusted preparatory to the cigarette rolling operation.

Fig. 3 is a similar view showing the first step of the operation.

Fig. 4 is a similar view showing the step at the termination of the actual rolling operation.

Fig. 5 shows the parts in a position in which the rolling operation is about to be completed.

Fig. 6 shows the completed cigarette.

In the embodiment of the invention illustrated in the drawing, the device is shown as incorporated in a pocket book type of tobacco pouch, comprising a bag 1 having the usual hinged closure including the frames 2 pivoted at 3 and provided with ball clasps 4. The device for rolling the cigarettes includes a plate 5 supported along the longitudinal edge of one of the frames 2 within the pouch. The forward end of said plate has an upwardly deflected lip 6 and is connected at its rearward end with a curved extension 7 lying beneath the edge of the frame when the pouch is open, so that it provides a support outside the pouch for conveniently supporting the pouch in the hands of the operator. The position normally assumed by the hand of the operator in operation of the device is such that the curved extension 7, with the section of the bag wall intervening, rests upon the middle finger of the right hand.

At each end of the plate 5 and adjacent to the longitudinal member of the frame are ears 8 that extend upwardly from the upper plane of the plate. Seated within the ears is a plate member 9 which is of a width approxi-

mately one-half the width of the plate 5. This plate 9 has an inwardly curved extension 10 of less length than the length of the plate 9 and provides a handle for the plate which is manipulated by the thumb of the operator. It will be understood that the plate 9, supported by the ears 8, is free to move across the surface of the plate 5. It is normally held in resilient contracted position by a resilient connection 11 preferably comprising a rubber band wrapped around the ends of the member 10 and connected with a permanent part of the longitudinal member of the frame, 2. The normal retracted position is clearly illustrated in Fig. 2 of the drawing, from which it will appear that the outer longitudinal edge of the plate 9 lies along the longitudinal margin of the frame 2, and the forward end of the plate 9 extends upwardly slightly from the face of the plate 5.

In operating the device for rolling a cigarette, the first operation is to place a longitudinal marginal edge of a cigarette paper 12 beneath the forward edge of the plate 9. The plate 9 is then depressed by exerting pressure on the curved member 10 by the thumb of the operator. This clamps the marginal edge of the cigarette paper between the forward edge of the plate 9 and the face of the plate 5. The cigarette paper is then turned backwardly to the position shown in Fig. 3 of the drawing. By slightly closing the pouch opening by bringing the frames together, the marginal edge of the plate 5 is depressed into the pouch and a quantity of tobacco necessary for making a cigarette is scooped upwardly on the forward edge of the plate 5 and against the surface of the upwardly inclined sheet of cigarette paper. The frame is then opened out to position shown in Fig. 4, the forward marginal edge of the cigarette paper being turned under the forward marginal edge of the plate 5 enclosing the tobacco in the manner illustrated in Fig. 4. The plate 9, clamping the marginal edge of the cigarette paper, is now moved forwardly by the thumb of the operator, which tucks the edge of the paper under the quantity of tobacco enclosed between the plate 5 and the interior of the sheet of paper, and brings the longitudinal edges of the paper in overlapping position around the filler for the cigarette.

In operating the device, the plate 9 is moved forwardly until it clears the edge of the plate 5, and the filled cigarette paper is then removed from the edge of the plates 5 and 9.

and sealed in the usual way, thereby producing a smooth, compact, firmly rolled cigarette, as shown in Fig. 6 of the drawing.

I am aware that the invention may be modified in numerous particulars, and that the pouch may be omitted and the cigarette rolling device constructed as an independent unit, if desired. However, the advantage in the combination of the device with the pouch will clearly appear.

I do not limit myself, therefore, to the exact construction shown and described, but what I claim and desire to secure by Letters Patent is:—

15. 1. A device of the class described comprising a support, a plate having free movement in respect of said support, and a resilient connection for said plate whereby the same may be moved while in clamping engagement 20 with a sheet of paper across the face of said support.

2. A device of the class described comprising a support for holding a quantity of tobacco, a plate arranged in clamping and 25 sliding engagement with said support adapted to engage a sheet of paper and roll the same around the tobacco on said support, and means connected with said plate for yieldingly holding the same in association with said support.

3. A device of the class described comprising a plate for holding a quantity of tobacco, said plate having an up-turned forward marginal edge, a second plate arranged to make 35 clamping and sliding engagement with said first named plate thereby to engage the margin of a sheet of paper, and roll the same around the tobacco on said first named plate, and means connected with said second plate 40 for yieldingly holding the same in association with said first named plate.

4. In a device of the class described, a frame, a plate supported by said frame, a finger hold for holding said frame, a second 45 plate yieldingly associated with said first

named plate, and a manipulative member on said second plate whereby the same may be moved into clamping engagement with said first named plate to hold the margin of a sheet of paper, and the second named plate 50 moved forwardly of said first named plate to roll a sheet of paper around a quantity of tobacco supported on said first named plate.

5. The combination with a tobacco pouch 55 having a pivoted frame, of a device for rolling cigarettes including a plate extending inwardly into the pouch and supported in connection with the frame, a second plate slidably operable across said first named plate, and a resilient connection between the frame 60 and said second named plate whereby said second named plate is normally held in inclined position with respect to said first named plate, said resilient connection permitting forward sliding movement of said 65 second named plate across the face of said first named plate.

6. The combination with a tobacco pouch 70 having a pivoted frame, of a device for rolling cigarettes including a plate extending inwardly into the pouch and supported in connection with the frame, a support in connection with said plate for holding the pouch, a second plate slidably operable across said first named plate, and a resilient connection 75 between the frame and said second named plate whereby said second named plate is normally held in inclined position with respect to said first named plate, said resilient connection permitting forward sliding movement of said second named plate across the face of said first named plate.

7. A device for rolling cigarettes comprising a support, a plate movable across the face of said support, and a connection for holding 80 said plate in assembled relation with said support and permitting free movement thereof while in clamped engagement with a sheet of paper.

BENJAMIN K. FISHER.
